(*) Notice: This patent is subject to a terminal disclaimer.

CLAIM

(**) Term: **14 Years**

The ornamental design for a two handle faucet, as shown and described.

DESCRIPTION

FIG. 1 is a front perspective view of the two handle faucet showing our new design;

FIG. 2 is a rear perspective view thereof;

FIG. 3 is a right side elevational view thereof;

FIG. 4 is a top plan view thereof;

FIG. 5 is a front elevational view thereof;

FIG. 6 is a rear elevational view thereof;

FIG. 7 is a left side elevational view thereof; and,

FIG. 8 is a bottom plan view thereof.

The broken line showing of the handles, lift rod and spout tip in FIG. 1 are for purposes of illustration only and form no part of the claimed design.

1 Claim, 8 Drawing Sheets
